ELGAN S. SLOAN, OF SHIPPENVILLE, PENNSYLVANIA

CONTENTS-DISCHARGING DEVICE FOR PUMP, DRILL, OR OTHER CYLINDERS

Application filed January 19, 1928. Serial No. 247,925.

This invention relates to devices or constructions providing for the discharge of the contents of pump, drill or other contents-retaining cylinders that are removed or being removed from a well bore, and relates more particularly to supporting means for such cylinders of a novel and advantageous construction which may be conveniently mounted on the derrick floor or other suitable support convenient to the operator.

In the drilling of wells, it is necessary to provide facilities for cutting into and breaking up material at the bottom of the bore and for confining the loose material so that it may be withdrawn from the well bore and discharged. The pump or drill cylinders which are utilized for this purpose usually have a valve inlet at their lower ends for both liquid and solids, or semi-solids, and a valved outlet at their upper ends through which liquid may pass until the space within the cylinder is practically filled with loose material, such as sand, pulverized rock, etc., at which time the cylinder is withdrawn from the well bore and its contents removed. Such a pump cylinder forms the subject matter of my prior Patent No. 1,656,798 granted January 17, 1928, and will be described and shown in connection with the device of the present invention to illustrate its application. While particularly designed for pump cylinders of this character, the present invention is, however, susceptible of use generally as a discharging support for contents-retaining cylinders, and consists in the combinations and constructions hereinafter pointed out and thereafter defined in the claims.

In the accompanying drawings illustrating a preferable embodiment of the invention and forming part hereof,

Figure 1 is a vertical sectional view of the support mounting the combined drilling and pumping cylinder of my patent aforesaid, with its lower valved inlet dropped with its plunger to discharge the contents trapped in the cylinder,

Figure 2 is a horizontal sectional view on the line 2—2 of Figure 1,

Figure 3 is a perspective detail of the cylinder seating support and discharge tube.

Referring to the drawings by numerals, 1 indicates a base having external edge flanges 2 adapted to overlap and be suitably bolted to the edges outlining an opening in a suitable support 3 which, for example, may be 55 the derrick floor.

The base is formed with a central opening therein and has its edge incut at one side (Fig. 2) to provide a lateral recess 4 giving access to said opening, whose edge is formed with an upwardly inclined flange 5, with its edge concaved to form an annular tube seat 6.

A tubular member 7 constituting a cylinder support and discharge funnel is mounted upon the annular seat 6, by means of an outwardly flaring external flange 8 intermediate of its ends, this flange having a diameter to seat on the support flange and having a convexed edge 9 contoured to fit the concave of the seat 6.

The interior of the member 7 at a point substantially midway of the tube is formed with an annular flange 10, whose annular horizontal face 11 forms a seat and support for the lower end of the pump, drill, etc., cylinder whose contents are to be discharged.

The interior walls of the tube above and below the seat flange 11 taper or flare outwardly in opposite directions, the lower taper 12 serving as a discharge funnel and as a guide to assist the contents discharging instrumentalities to return back into the cylinder. The upper tapered portion 13, while preferably upwardly and outwardly tapered as a means for guiding the lower edge of the drill or pump cylinder to rest on the flat horizontal seat 11, does not require the same degree of taper as the discharge funnel 12 since it is desirable that the lower edge of the pump or drill cylinder rests upon the flat annular seat 11, thereby positioning the axis of its bore in alinement with the axis of the discharge funnel.

The device of the present invention, while particularly desirable for use in connection with combined drill and pump cylinders of the type shown and described in my prior patent aforesaid, is as previously stated, adaptable for use in connection with other

types of cylinders providing means for discharging their accumulated contents. In the drawings, in Figure 1, I have shown a cylinder 14 of the type of my prior patent aforesaid, housing an operating rod 15 for a combined drill head and piston 16 having bores 17 therein covered by flap valves 18 permitting sand, silt, etc. to enter, but retaining it within the cylinder or barrel. A cap valve 19 at the upper end of the cylinder or pump barrel 14 provides means by which liquid may pass up through the upper part of the barrel.

It will be obvious in the use of the described invention, the lower end of a pump or drill cylinder 14 is inserted in the upper end of the tubular member 7 with its lower edge resting upon the annular seat 11 internally thereof. The valved pump or drill piston 16 which, in the normal use of the cylinder, remains within the same and retains the accumulated solids and semi-solids within the barrel by reason of the closed flap valves 18, is now lowered from the cylinder so that the accumulation therewithin may drop by gravity from the barrel and through the discharge funnel 12. The barrel may be tapped on its seat 11 to jar loose any portion of its contents remaining after the piston head has been lowered. Upon the return movement of the piston to close the valve, the outwardly flaring sides of the funnel portion 12 will center the piston relatively to the barrel and guide it back into proper position therein. A device as described provides an expeditious way for cleaning the barrels of their accumulation of sand, etc., and because of its nature, may be readily incorporated in the derrick flooring where it is most conveniently located for this purpose. While the invention has been illustrated as incorporated in a specific form having a special relation to the pump and drill barrel of my patent aforesaid, it is to be understood that this specific form is illustrative rather than restrictive; that it may be combined in use with contents retaining cylinders of varying constructions providing contents retaining means which may be lowered below the seated end of the cylinder to permit gravity discharge of the cylinder contents; and that various modifications and adaptations of the invention will be permissible within its scope and that of the appended claims.

What I claim and desire to secure by Letters Patent is: .

1. A device of the character described comprising a base having its edge formed to overlie the edges of an opening in a stationary support and having an aperture therein edged by a supporting flange, and a member of tubular formation and having an external supporting flange of a diameter to overlie and rest upon the edge flange of said base

aperture, said tubular member extending downwardly from said flange through said aperture in the base plate and flaring outwardly and being provided with an internal annular flange forming a cylinder seat above its lower end. 70

2. A device of the character described having an apertured stationary base plate provided with an elevated supporting flange edging its aperture formed with a concaved seat and with a lateral slot extending inwardly from its edge to said aperture, and a member of tubular formation having a diameter permitting its insertion through said lateral slot and provided with an external upwardly tapering annular flange of a diameter to overlie said supporting flange and formed with a correspondingly convexed seat engaging surface, said tubular member having an internal annular cylinder seat positioned at a point above its lower end. 80

3. A device of the character described having in combination a base plate having its edges formed to overlie the edges of an opening in a stationary support and provided with an aperture therein edged by a supporting flange, said base plate having a lateral slot extending inwardly from one edge providing an entrance to said aperture, and a tubular member having an external flange thereon of a diameter to overlie and rest upon said edging flange and having below said flange a diameter insertible through said lateral slot, said tubular member being formed with an internal annular cylinder supporting shelf above its lower end. 90

4. A device of the character described comprising in combination with a stationary support having a slot extending inwardly from one edge thereof, a base plate having its edge formed to overlie the edges of said slot, having an aperture therein edged with a supporting flange, and having a lateral slot extending inwardly from one edge thereof in alignment with the supporting slots providing an entrance to said aperture, a tubular member having a diameter permitting its insertion through said lateral slot and having an external flange thereon of a diameter to overlie and rest upon said edging flange, said tubular member having an annular internal flange providing a cylinder seat and depending from said aperture with its walls below said seat outwardly tapering. 100

5. A device of the character described having in combination, a base plate having an aperture therein within its edges and a communicating lateral slot extending inwardly thereto from one edge, and a tubular member having an external flange of a diameter to overlie and rest upon said base plate at the edges of its aperture and having its walls oppositely and outwardly flared from an intermediate point of minimum diameter insertible through said lateral slot, said tubular 110

member being formed with an internal annular cylinder supporting shelf adjacent to said point of minimum diameter.

6. A device of the character described, comprising a fixedly supported base plate having an aperture therein within its edges and a lateral communicating slot extending inwardly thereto from one edge, and a tubular member having an external diameter insertible through said slot and provided with means overlying and resting on said base plate at the edges of its aperture, said member depending through said aperture and having its interior provided with an annular cylinder seating flange above its lower end.

10 Signed at Shippenville in the county of Clarion and State of Pennsylvania this eleventh day of January, A. D. nineteen hundred twenty eight.
